US00D876354S

(12) **United States Design Patent** (10) **Patent No.:** **US D876,354 S**
(45) **Date of Patent:** **** Feb. 25, 2020**

(54) **CONNECTOR**

(71) Applicant: **EmCom Technology Inc.**, Taipei (TW)

(72) Inventor: **Chu-Li Wang**, Taipei (TW)

(73) Assignee: **EMCOM TECHNOLOGY INC.**,
Taipei (TW)

(**) Term: **15 Years**

(21) Appl. No.: **29/638,888**

(22) Filed: **Mar. 1, 2018**

(30) **Foreign Application Priority Data**

Sep. 1, 2017 (TW) 106213048

(51) **LOC (12) Cl.** **13-02**

(52) **U.S. Cl.**

USPC **D13/120**

(58) **Field of Classification Search**

USPC D13/119, 120, 133, 146, 149, 154, 199

CPC H01R 12/57; H01R 12/714; H01R 11/24;

H01R 11/281; H01R 11/286

See application file for complete search history.

(57) **CLAIM**

The ornamental design for a connector, as shown and described.

DESCRIPTION

FIG. 1 is a front perspective view of a connector showing my new design;

FIG. 2 is a rear perspective view of a connector showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIGS. 9 and 10 are perspective views of the connector, shown in an environment of use.

The broken lines shown represent portions of the connector that form no part of the claimed design.
